FOAM BUBBLE BLOWING TOY

Gordon W. Holt, Jr., Arcadia, Calif., assignor to Wham-O Mfg. Co., San Gabriel, Calif., a corporation of California

Filed May 20, 1968, Ser. No. 12,008

Term of patent 14 years

Int. Cl. D21—02

U.S. Cl. D34—15

FIG. 1 is a front perspective view of a foam bubble blowing toy showing my new design; and

FIG. 2 is a bottom view of the apparatus of FIG. 1.

I claim:

The ornamental design for a foam bubble blowing toy, as shown.
